UNITED STATES PATENT OFFICE

2,556,615

LAMP SUPPORTING CLAMP FOR VEHICLES
AND THE LIKE

Charles C. De Vaughn, Sharonville, Ohio

Application March 10, 1947, Serial No. 733,703

2 Claims. (Cl. 248—226)

1

This invention relates to new and useful improvements in lamp holding clamps for vehicles and the like and the primary feature of the present invention is to provide a clamping device that is quickly and readily attached to a vehicle, trailer or the like for supporting a small light commonly referred to as an emergency lamp.

Another important feature of the present invention is to provide a device of the character referred to comprising a movable jaw that is connected to a stationary jaw by spring means whereby the jaws may be spread apart under tension to grip opposite sides of a fender or the like.

A further feature of the present invention is to provide a clamping device supporting emergency lamps including a movable jaw having a pad on its inturned end to grip the fender or the like without in any way injuring the finish of the latter.

A still further feature of the present invention is to provide a device of the class described that is simple and practical in construction, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the lamp holding clamp applied to a vehicle fender;

Figure 2 is an enlarged perspective view of the clamp;

Figure 3 is a side elevational view of my improved clamp, and

Figure 4 is a sectional view taken on the line 4—4 of Figure 2.

Referring now to the drawings in detail, wherein for the purpose of illustration I have disclosed a preferred embodiment of the present invention, the numeral 5 represents an elongated fixed arm having its upper end turned outwardly to form a jaw 6 having its outer edge formed with serrations as at 7.

A pair of ears 8 extend outwardly from the sides of arm 5 and are adapted to overlie a pair of ears 9 extending outwardly from a movable arm 10.

The respective pairs of ears are connected by a pin or the like 11 for permitting pivotal movement of arm 10 toward and away from fixed arm 5.

One end of member 5 is turned inwardly to

form a jaw 12 having a protective preferably rubber pad 13 secured to its outer edge by usual fastening means 14 seated in recesses 15 in said pad so that the outer face of the pad will be smooth.

Said jaw 12 is adapted to be positioned below the jaw 6 of arm 5 and said jaw 12 is held against arm 5 by a usual substantially U-shaped wire spring 16 that bears inwardly against the upper end of arm 5 and is looped inwardly around pin 11 as at 16a to provide tension coils for the spring and said spring having its ends 17 bearing against the lower portion of arm 10 as shown in Figure 2 of the drawings.

15 The lower end of arm 10 is curved outwardly as at 18 away from arm 5 to permit said lower end to bear against the lower end of arm 5 so that the jaw 12 and pad 13 are spaced from arm 5 as shown by dotted lines in Figure 3.

20 Openings 19 are suitably placed in arm 10 to receive fastening means by which a conventional emergency lamp or the like 20 is supported to the arm 10.

25 In operation of the device it is merely necessary to bring the lower ends of arms 5 and 10 together to provide a space between arm 5 and jaw 12 between which a fender 21 extends. The arm 10 is then released and spring 16 causes the jaws 6 and 12 to bear inwardly against the fender 30 to conveniently support a lamp as shown in Figure 1.

35 In view of the foregoing description taken in conjunction with the accompanying drawings it is believed that a clear understanding of the device will be quite apparent to those skilled in this art. A more detailed description is accordingly deemed unnecessary.

40 It is to be understood, however, that even though there is herein shown and described a preferred embodiment of the invention the same is susceptible to certain changes fully comprehended by the spirit of the invention as herein described and the scope of the appended claims.

45 What I claim is:

1. A lamp supporting clamp of the class described comprising an elongated fixed arm having a jaw laterally formed at its upper end, gripping serrations formed on the outer edge of the jaw, a movable jaw pivotally secured to the fixed 50 jaw intermediate its ends and having a lateral jaw formed on its upper end and positioned below the jaw on the fixed arm, a protective pad formed on the outer edge of the second named jaw, spring pressure means connecting said arms and normally holding the second named jaw

against the fixed arm, said jaws being adapted to bear inwardly and grip upon opposite sides of a supporting structure, and means formed with one of the arms for receiving a lamp supporting bracket.

2. A lamp supporting clamp for detachably securing a lamp to the fender of a vehicle comprising a pair of complementary arms pivotally connected together intermediate their ends with their inner surfaces in spaced face to face relationship, one of said arms being shorter than the other and having a lateral inwardly extending padded jaw formed on its upper end, a lateral jaw formed on the upper end of the other arm and overlying the first-named jaw, gripping serrations formed on the outer edge of the last-named jaw, spring pressure means connecting said arms and normally holding the jaws against

the inner and outer surfaces of a fender and means for attaching a lamp to one of said arms.

CHARLES C. DE VAUGHN.
